THOMAS A. DICKS, OF WILKINSBURG, PENNSYLVANIA.

GUARD FOR MACHINE-TOOLS.

1,201,042.

Specification of Letters Patent. Patented Apr. 15, 1919.

Application filed June 6, 1918. Serial No. 101,913.

To all whom it may concern:

Be it known that I, THOMAS A. DICKS, a subject of the King of Great Britain, and a resident of Wilkinsburg, in the county of Allegheny and State of Pennsylvania, have invented a new and useful Improvement in Guards for Machine-Tools, of which the following is a specification.

My invention relates to safety attachments for punch presses and other reciprocating machine tools, and it has for its general object to provide a rugged and dependable guard structure which shall effectively prevent injury to the operator of the machine.

One of the more specific objects of my invention is to provide a safety attachment for punch presses and the like in which the operation of the press depends directly upon the operation of the guard, whereby the press cannot operate until the guard is in its operative or safety position.

A further object of my invention is to provide a safety attachment of the character above indicated in which the guard, when once moved to its safety position, is positively prevented from leaving such position until the press or other machine tool has operated.

In the accompanying drawing, Figure 1 is a side elevational view of a punch press equipped with a safety attachment constructed in accordance with my present invention, only so much of the press being shown as is necessary to illustrate the safety attachment. Fig. 2 is a front elevational view of a portion of the structure of Fig. 1, particularly illustrating the mechanism for holding the guard in its safety position until the press has operated, and Fig. 3 is a fragmentary plan view illustrating the construction of a supporting frame which forms a part of my safety attachment.

The press shown in Fig. 1 consists of side frames 1 upon which is supported a stationary die 2 and a reciprocating punch 3, the punch being carried by a vertically reciprocating cross-head 4 which slides upon guides 5 carried in the machine frame and which is reciprocated by means of the usual eccentric or crank mechanism 6 carried by a crank shaft 7 which is adapted to be intermittently coupled to the shaft of a driving wheel 8. The parts thus far described are of well-known construction and form no part of my present invention.

Pivotedly supported upon short pins 10 on opposite sides of the machine, are supporting castings 11 which carry parallel channel bars 12 which extend from the front to the rear of the machine and are connected across the back of the machine to form a rigid frame. As shown, this connection is made by bending the rear ends of the channel bars 12, as shown in Fig. 3, and connecting the bent ends of the bars by means of a third bar 13. Near their front ends, the parallel channel bars 12 carry supports 14 from which is suspended, by means of upright arms 15, a guard consisting of a bar 16 adapted to rest edgewise upon the die 2 and a rectangular frame 17 covered wholly, or in part, with wire netting 18. The supports 14 are slidable along the bars 12, and the arms 15 are also slidably secured in the supports 14, the position of each of the supports 14 being fixed by means of a thumb screw 19 which also serves to fix the position of the arm 15 with respect to the support 14.

The frame formed by the parallel channel bars 12, the connecting bar 13 and the guard bars 15 and 16 is reciprocated around the pivot pins 10 by means of a treadle 20 pivoted to the frame of the machine at 21 and normally drawn upward by means of a spring 22. The treadle is connected, by means of a link 23, to a lever 24 pivoted at 25 and attached, at its free end, to the lower end of a link 26 which is pivotally secured to a pin 27 carried by a cam plate 28 that is loosely mounted upon a pin 29 secured to the machine frame. The cam plate 28 is provided with a curved surface 30 which engages a roller 31 that is rotatably carried by the pivoted support 11. A press-operating link 32 is operatively connected, at its upper end, to a bell-crank lever 40 which is adapted to actuate a clutch 41 through which motion is imparted to the crank shaft 7, and which is normally pressed upwardly by means of a spring 42. At its lower end, the link 32 carries a slotted member 33 which surrounds the pin 27 and thereby establishes a lost-motion connection between the link 32 and the link 26. The linkage mechanism just described is so arranged that, when the treadle 20 is depressed, the cam plate 28 is rotated in a counter-clockwise direction around the pivot pin 29 and, by reason of the engagement between the cam surface 30 and the roller 31, rocks the guard-

carrying frame around the pivot pins 10 from the position shown in full lines in Fig. 1, to the position shown in dotted lines, in which latter position the bar 16 of the guard 5 rests upon the die plate 2. When the guard has reached the latter position, the pin 27 is brought to the lower end of the slot, in the member 33 and pulls the link 32 downward, thus actuating the clutch mechanism 10 to operate the press. If, however, the bar 16 of the press, in its downward movement, encounters the hand of the operator or any other obstruction, the pin 27 will not be lowered far enough to exert a pull upon the 15 link 32, and the press will therefore not be operated until such obstruction is removed from beneath the guard. When the treadle is released, the guard is returned to its upper position by means of a spring 43 or by 20 means of a suitable counterweight at the rear of the guard frame.

The structure described above is sufficient for the proper operation of the guard while the press is normally running. There is a 25 possibility, however, that, when the press is idle, the treadle may be depressed and the cycle of operations described above may be performed without, however, actuating the press. Under these circumstances, the clutch 30 will remain connected until power is applied to the press, but the guard will be allowed to return to its raised or inoperative position, and, when the press is first started, the punch 3 will make one reciprocation with 35 out being protected by the guard. In order to prevent such an occurrence, I provide a latch which holds the guard in its downward or operative position until the press has made a working stroke. This latch is 40 best shown in Fig. 2 of the drawing and consists of a flat annular member 35 loosely pivoted at 36 to the machine frame and provided, at its lower end, with a notch 37 which is adapted to engage the upper and inner 45 angle of the adjacent channel bar 12 when the bar is in its lower position. The weight of the latch member 35 is so distributed around the pivot 36 that the member tends to assume its latching position shown in full 50 lines in Fig. 2. Secured to the cross-head 4 adjacent to the upper curved end of the latch 35 is a slotted plate 38 which is adjustably secured to the cross-head by means of bolts 39.

55 In the operation of the latching mechanism described above, the parts are in the positions shown in full lines in Fig. 2 at the beginning of each stroke of the machine.

When the frame which carries the guard moves downward, it deflects the latch 35 to the left, and, as soon as the frame has passed below the latch, the latch will immediately swing back far enough to bring the notch 37 into holding engagement with the adjacent bar 12, and this relation will be maintained 60 until the cross-head 4 descends and brings the member 38 into sliding engagement with the upper curved end of the member 35, thereby rotating the latch again around its pivot and releasing the bar 12 which permits the frame to rise to its inoperative position.

It will be observed that the safety device which I have shown and described is so related to the operating parts of the press as 75 to effectually protect the operator from injury and that it is substantially impossible for the press to operate except when the space around the punch and the die is unobstructed. It will also be understood that 80 this device is capable of numerous structural modifications while retaining the essential features of my invention, and I therefore desire that no limitations shall be imposed upon my invention except such as are indicated in the appended claims.

I claim as my invention:

1. A safety attachment for punch presses and similar machine tools comprising a pivoted supporting arm, a guard carried thereby, a lever mechanism for bringing the guard into operative position and for thereafter operating the press, a latch normally tending to swing into the path of movement of the said arm, and means associated with 90 a moving part of the machine for deflecting the said latch from the path of the said arm.

2. A safety attachment for punch presses and similar machine tools comprising a pivoted supporting arm, a guard carried thereby, a lever mechanism for bringing the guard into operative position and for thereafter operating the press, an angular latch pivotally attached to the frame of the machine and normally tending to swing one 100 of its arms into the path of movement of the said arm, and a member carried by a moving part of the machine and adapted to engage the other arm of the said latch at predetermined intervals to swing the said 110 latch and release the said arm.

In testimony whereof, I have hereunto subscribed my name this 31st day of May, 1916.

THOMAS A. DICKS.
